UNITED STATES PATENT OFFICE.

WILLIAM L. OSBORNE, OF CHICAGO, ILLINOIS, ASSIGNOR TO THE RICHARDSON-PHENIX CO., OF MILWAUKEE, WISCONSIN, A CORPORATION OF WISCONSIN.

SELF-ACTING CUSHION AND CHECK VALVE.

1,252,940.

Specification of Letters Patent.

Patented Jan. 8, 1918.

Application filed March 10, 1911, Serial No. 613,634. Renewed May 31, 1917. Serial No. 172,076.

To all whom it may concern:

Be it known that I, WILLIAM L. OSBORNE, a citizen of the United States, and a resident of Chicago, in the county of Cook and 5 State of Illinois, have invented certain new and useful Improvements in Self-Acting Cushions and Check Valves; and I do hereby declare that the following is a full, clear, and exact description thereof, reference being 10 had to the accompanying drawings, and to the characters of reference marked thereon, which form a part of this specification.

This invention relates to improvements in self-acting valves of that kind in which 15 the valve piece is moved off its seat by a superior pressure below, and is automatically returned to its seat when the pressure above exceeds the pressure beneath the valve piece.

20 The invention relates to a construction and arrangement for cushioning the blow of the valve piece when it is automatically seated to prevent wearing impact of the valve against the seat, and relates also to an improved 25 means for protecting the valve seat and the valve piece from wear, due to the wire drawing action of the fluid, upon the opening and closing movements of the valve piece. Certain of the features are also adapted to 30 manually operated valves.

As shown in the drawings,—

Figure 1 is an axial section of a valve embodying my improvements.

Fig. 2 is a similar section showing a modification.

The casing 10 of the valve shown in Fig. 1 is provided with branches 11 and 12 which are shown as interiorly screw-threaded for connection with the sections of a piping line 40 in which the valve is incorporated. The casing is provided with an interior diaphragm 14, of common form, having a horizontally apertured portion 15 which carries the body seat of the valve. The body seat is 45 herein shown as formed on a separate ring 16 which is screw-threaded to the diaphragm and has a limiting or stop flange 16' which engages the upper face of the horizontal portion of the diaphragm to limit its insertion thereinto. The ring is provided at its 50 upper end with an interior annular conical seat 17 adapted for engagement with a downwardly facing, annular conical seat 19 on the valve piece.

55 The said valve piece 18 is guided in its

movement toward and away from the body seat by the guide fingers 20 made integral with and extending downwardly from a hollow plug 21 that is screw-threaded in an upwardly opening nipple of the valve casing, and by other guide fingers 22 extending downwardly from the valve piece through and engaging the seat ring 16. The valve piece is formed at its top with an annular recess 24 and is provided with a central stop lug 25 to engage a stop lug 26 extending downwardly from the top wall of the hollow plug 21 whereby the opening movement of the valve is limited. The hollow plug is in communication with the interior 70 of the valve casing above the valve piece through the spaces between the guide fingers 20, and when the upper edge of the valve piece rises above the lower edge 27 of the interior of the plug a body of fluid is imprisoned in the hollow plug which cushions the opening of the valve, as will be evident. The imprisoned fluid may escape slowly from the chambered plug through an opening 28 which extends to the exterior of the 80 valve piece. The pressure on the upper and lower sides of the valve piece is also equalized through said opening to permit the valve to be closed at a time when the upper edge of the valve piece is above the edge 27 85 of the chambered plug.

The valve piece is provided on its lower side with a concentrically arranged extension 29 which, as herein shown, is made integral with the valve piece. The said extension 29 extends into and has a close slip fit with the ring 16, or other passage which connects the two sides of the valve, at the most restricted diameter of said passage. The restricted diameter of the ring in which 95 said extension 29 fits when the valve is closed is located a distance below the plane of the body seat somewhat less than the distance between the plane of the seating face of the valve piece and the lowest part of the 100 extension 29. There is formed between the extension 29 and the seating face of the valve piece a chamber 30 which may be augmented by cutting away the seat ring at 31.

The arrangement of the extension 29 is 105 such, with respect to the valve piece seat, that said projection remains in the most restricted part of the opening of the seat ring until the valve piece is moved a substantial distance from the body seat, and enters said 110

passage before said valve piece closely approaches the body seat. The extension 29 therefore receives the wear due to the high velocity of the fluid passing through the 5 valve, and the body seat and valve piece seat are thus protected against such wear.

The said chamber 30 formed in the valve piece, and partially in the seat ring if desired, has the further function of receiving 10 and imprisoning therein some of the material which is flowing through the valve at a time when the valve piece is being closed, and the material thus imprisoned constitutes a cushioning element which cushions the 15 blow of the closing valve and prevents the valve piece striking the body seat with such force as to injure the parts. The body of material thus imprisoned in the chamber 30 escapes slowly therefrom between the body 20 seat and valve piece seat and between the extension and restricted portion of the passage in the seat ring when the valve is closed, and thus substantially slows the movement of the closing valve piece with the result 25 stated. The said projection 29 and the concentric chamber 30 above the same thus performs the double function of protecting the body and valve piece seats from the wearing action of the fluid and also protects 30 said seat from the pounding action of the valve when it closes.

The construction shown in Fig. 2 is generally similar to that shown in Fig. 1, and similar parts bear the same reference numbers. As shown in said Fig. 2, there is provided at both radial sides of the valve seat or radially within or radially outside of the valve seat a cushioning chamber, the lower cushioning chamber 30 and extension 40 29 being like the same parts shown in Fig. 1.

As shown in said Fig. 2, the flange 33 of the body seat ring 16 shown in Fig. 2 is provided with an upstanding flange 34, and the valve piece is made of a diameter above 45 the valve seat to close fit within said flange 34, as shown at 35. The said valve piece is provided above its seat 19 with an annular chamber 36, having the same function as the chamber 30. The chamber 36 is formed to 50 provide on the valve piece, around the same, a lip 37 which enters and closely fits within the flange 34, and preferably the lip 37 will be made of such length as to give it a slight lead beyond the projection 29 into the seat 55 ring 16 so that it will enter the flange 34 just before said projection 29 enters the restricted portion of the seat ring.

With the construction shown it will be seen that the material or fluid passing 60 through the valve will be imprisoned in both of the chambers 36 and 30, one above and the other below the body seat, thereby providing a large cushioning body of the material to cushion the seating force of the valve 65 piece. Inasmuch as the lip 37 enters the

flange 34 prior to the entrance of the extension 29 into the restricted portion of the body seat ring, the fluid imprisoned will first escape between the projection 29 and the body seat ring and after the latter projection has entered the restricted portion of the body seat ring the fluid will be forced out also between the lip 37 and the flange 34. The valve shown in Fig. 2 is more especially adapted to compressible fluids, such as air, steam and gas, although it may be used with valves adapted for use with liquids.

By reason of the close fit between the lip 37 and the flange 34 and the fact that the lip 80 remains within the flange until the valve piece and body seats are separated a substantial distance when the valve opens, and enters said flange 34 while the seats are yet separated a substantial distance when the 85 valve is closing, it will be seen that the said lip 37 and flange 34 acts in the same manner as does the projection 29 to protect the body and valve piece seats by taking the wire drawing action of the fluid passing through 90 the valve. Thus in the construction under discussion the wearing or wire drawing action of the high velocity fluid passing through the valve at the moment of opening or closing is distributed between the 95 projection 29 and the flange 34. It will be furthermore obvious that the flange 34, co-operating as it does with the valve piece which fits closely therein, may be employed alone for protecting the valve piece and 100 body seats from the wire drawing action of the fluid passing through the valve, in the same general manner that the projection 29 is employed for protecting the valve seat. The said part 29 constitutes an elongated 105 projection of the valve seat, while the part designated by 35 constitutes a radial projection of the valve piece for the same purpose. It will be furthermore obvious that so far as the seat protecting function of the 110 lip 37 and the flange 34 is concerned, said parts may be employed on other than automatic or self-opening and closing valves, as for instance, valves having manually operable stems or like members to open and close 115 the valve.

In the construction shown in Fig. 2, by reason of the greater lift of the valve piece, the hollow plug 21 thereof is made slightly longer, and the valve piece itself may be 120 provided with guide fingers 38 to engage the inner cylindric surface of the chambered plug.

It will be understood that the construction shown is capable of some variation within 125 the spirit and scope of the invention, and the invention is not limited to the particular construction shown except as imposed by the prior art. For instance, the essential features of the self-acting cushioning valve 130

described may be employed in a pump valve for pumping either gas or liquid, and the seats may be made otherwise than conical, metal to metal seats.

5 I claim as my invention:—

1. A self-acting cushioned valve having a casing provided with an annular single facing tapered body seat, a valve piece which is provided with a single facing tapered seat 10 to engage the body seat adapted to be freely movable toward and from the body seat by pressure of fluid moving through the valve, and fluid imprisoning means of substantial capacity located at both radial sides of the 15 body seat to cushion the closing movement of the valve piece against the body seat.
2. A self-acting cushioned valve having a casing provided with an annular body seat, and a valve piece which is freely movable 20 toward and from the body seat and adapted to be actuated by movement of fluid through the valve, there being two chambers in the valve piece each of a substantial area and one disposed at each radial side of the body 25 seat and which coöperate with a fixed part of the valve structure to receive and imprison therein bodies of fluid to cushion the closing movement of the valve piece against the body seat.
3. A self-acting cushioned valve comprising 30 a casing provided with an annular body seat which surrounds the passage that connects the two sides of the valve, and a pressure actuated valve piece movable toward and from the body seat, said valve piece being provided with an extension which fits closely in a restricted portion of the passage below the body seat, an annular flange above and concentric with and spaced radially 35 from the body seat, the valve piece above the seat being enlarged to fit closely within said flange, and said extension and valve piece being arranged to maintain a restricted area for fluid flow between the same and the parts 40 within which they closely fit when the valve piece is a substantial distance from the body seat, there being formed chambers in the valve piece above and below the body seat to imprison bodies of fluid to cushion the closing movement of the valve piece against the body seat.
4. A self-acting cushioned valve comprising 45 a casing provided with an annular body seat which surrounds the passage that connects the two sides of the valve, and a pressure actuated valve piece movable toward and from the body seat, said valve piece being provided with an extension which closely fits in a restricted portion of the passage 50 below the body seat, an annular flange above and concentric with and spaced radially from the body seat, the valve piece above the body seat being enlarged to fit closely within said flange, and said extension 55 and valve piece being arranged to maintain
- a restricted area for fluid flow between the same and the parts within which they closely fit, when the valve piece is a substantial distance from the body seat, there being formed chambers in the valve piece at both radial 70 sides of the body seat to imprison bodies of fluid to cushion the closing movement of the valve piece against the body seat, the upper enlarged part of the valve piece being of a length to enter the flange before the projection enters the restricted portion of the passage.
5. A valve having an annular seat surrounding the passage which connects the two sides of the valve, the diameter of the 80 passage at one side of the valve being less than the said seat and at the other side thereof being greater than the said seat, and a valve piece movable toward and from said seat and formed with parts which closely fit 85 said smaller and larger diameters of said passage at the opposite sides of the seat.
6. A valve having an annular seat surrounding the passage which connects the two sides of the valve, and a valve piece 90 movable toward and from the seat, the passage at one side of the valve seat being of a diameter greater than the valve seat and the valve piece having a part which enters and closely fits the larger diameter of said passage, the entrance to said greater diameter 95 passage being unbroken and the contact between it and the valve piece being of a length in the direction of the axis of the valve piece to maintain a restricted area for 100 fluid flow between the same and the part of the passage in which it fits when the valve piece is a substantial distance from its seat to protect the valve seat from the wire drawing action of the fluid upon the opening and 105 closing movements of the valve piece.
7. A valve having an annular seat surrounding the passage which connects the two sides of the valve, and a valve piece 110 movable toward and from the seat, the passage at one side of the valve seat being of a diameter greater than the valve seat and the valve piece having a part which enters and closely fits the larger diameter of said passage, the entrance to said greater diameter 115 passage being unbroken and the contact between it and the valve piece being of a length in the direction of the axis of the valve piece to maintain a restricted area for 120 fluid flow between the same and the part of the passage in which it fits when the valve piece is a substantial distance from its seat to protect the valve seat from the wire drawing action of the fluid upon the opening and closing movements of the valve piece, there 125 being an annular chamber in the valve piece radially exterior to the valve seat and between the valve seat and said larger diameter of the passage.
8. A valve comprising a casing having an 130

- 4
- internal diaphragm provided with a screw-threaded opening, a seat ring screw-threaded in said opening, and provided at its upper end with a flange of larger diameter than 5 the opening in the ring, a valve piece movable toward and from the seat ring and having a part which fits closely within said flange, the part which fits in said flange being of a length to maintain a restricted 10 area for fluid flow between the same and the flange when the valve piece is a substantial distance from its seat, and an annular chamber surrounding the valve piece above the seat ring, said seat ring being provided with 15 a restricted passage and the valve piece being provided with an extension which fits closely thereinto and provided also between the extension and the valve seat with an annular chamber.
- 20 9. A self-acting cushioning valve comprising a casing provided with an inlet and with an outlet and provided therebetween with a thoroughfare surrounded by an annular body seat, said casing provided axially 25 in line with said seat with an opening closed by a removable member, which latter is provided with a cushioning chamber, a pressure-actuated valve piece guided by the walls of said thoroughfare and said cushioning 30 chamber and movable toward and from said seat and adapted to close the cushioning

chamber to cushion the opening movement of the valve, the wall of the thoroughfare and valve being formed within said thoroughfare to provide a fluid imprisoning 35 chamber to cushion the closing movement of the valve.

10. A valve having an annular seat, a valve piece movable toward and from the seat, the fluid conduit at one side of the seat being of greater diameter than the said seat, and the valve piece having an enlarged part which enters and closely fits the larger diameter of said conduit in advance of the seating of the valve piece, the clearance between said larger diameter of the conduit and the enlarged part of the valve piece being so small as to check the flow of material through the valve upon the opening and closing of the valve and thereby protect 40 the seat and the valve piece from the wire drawing action of the material passing through the said valve.

In testimony that I claim the foregoing as my invention I affix my signature in the presence of two witnesses, this 4th day of March A. D. 1911.

WILLIAM L. OSBORNE.
